SLIDING BEADS GAME BOARD

Dale K. Welbourn, P.O. Box 26, Neola, Iowa 51559

Filed July 7, 1971, Ser. No. 160,580

Term of patent 14 years

Int. Cl. D21—01

U.S. Cl. D34—5 SS

FIG. 1

FIG. 2

FIG. 3

FIG. 4

FIG. 5

FIG. 1 is a perspective view from the forward-leftward-top direction of a preferred embodiment of my new design relating to sliding beads game board.

FIG. 2 is a rearward elevational view of the FIG. 1 embodiment of my sliding beads game board.

FIG. 3 is a right side elevational view of the FIG. 1 embodiment, the left side elevational view being a substantial mirror image thereof.

FIG. 4 is a sectional elevational view taken along lines 4-4 of FIGS. 1, 2, and 5.

FIG. 5 is a top plan view of an alternate embodiment of FIG. 1 for sliding beads game board.

I claim:

The ornamental design for sliding beads game board, as shown.
